UNITED STATES PATENT OFFICE.

ANDREW DAHLSTROM, OF ASHTON, MICHIGAN.

ADVERTISING OR DISPLAY DEVICE.

SPECIFICATION forming part of Letters Patent No. 400,549, dated April 2, 1889.

Application filed August 24, 1888. Serial No. 283,669. (No model.)

To all whom it may concern:

Be it known that I, ANDREW DAHLSTROM, residing at Ashton, in the county of Osceola and State of Michigan, have invented new and useful Improvements in an Advertising or Display Device, of which the following is a specification.

My invention has for its object the construction of a device which may be used in various places—such as railroad-stations, hotel-lobbies, &c., but is more especially adapted for use in dining-rooms of hotels and dwellings—and which is arranged to automatically revolve and display different advertisements, bills of fare, scripture-texts, or any other object which is desired to be presented to view.

My invention consists in a cylindrical body provided with a series of openings in its sides, and a tape or ribbon upon which is printed, painted, or otherwise produced the various advertisements, texts, or other objects to be presented, and these objects are so placed upon the ribbon as to always be in alignment with one of the various openings when said ribbon is revolved. The ribbon is retained in said circular body and arranged therein upon rollers—one at each of the ribbons—one of which rollers is adapted to unwind while the opposite roller will wind up the ribbon.

Suitable gearing devices are employed to operate the rollers and the body; and the invention further consists in the peculiar combination and the novel construction of parts, as will be hereinafter fully described in the specification, and particularly pointed out in the claims.

As my invention is more especially intended to be used in connection with self-waiting tables, I shall describe the same in connection with a table, reference being had to the accompanying drawings, in which—

Figure 1 is a vertical section of my device, showing the same in connection with a portion of a table. Fig. 2 is a plan view of the device with the top casing removed. Figs. 3, 4, and 5 are horizontal sectional views on the lines 3 3, 4 4, and 5 5, Fig. 1. Fig. 6 is an enlarged sectional view of the central core and roller, and Figs. 7 and 8 are detail views hereinafter referred to.

In the practical application of my improve-

ment I provide a central opening, *a*, in the table *A* or other framing to which the same may be attached, and a suitable metallic frame, *B* *B'*, is provided to support the lower portions of the device. Projecting downwardly from the table-top is a hollow shaft, *C*, the lower end of which rests upon the lower bar, *B'*, of the frame *B*. Disposed to one side of the shaft *C* beneath the table and journaled in the frame *B* is the drum-shaft *D*, upon which is mounted and has one end secured thereto the power-spring *E*, the opposite end of said spring being attached to the frame *B*. This shaft is provided with the usual pawl-and-ratchet device, *d'*, and has secured upon its lower projecting end, *d*², a handle, *d*³, by means of which the spring *E* may be wound up when so desired.

*d*⁴ is the drive-gear operated by said spring *E*, which meshes with a pinion, *e*, mounted upon the lower end of the central shaft, *C*, by means of which motion is imparted thereto.

U is a plate disposed upon the lower plate of the frame *B'*, beneath the spring *E*, and is provided with a slot encompassing the drum-shaft and provided with a projecting finger, *u*, adapted to engage with a notched hub, *e'*. The opposite end of the plate *U* is provided with a rod-like projection, *u*², which projects through the side of the table-frame and is provided with a handle, *u*³. By this arrangement it will be seen that when the plate *U* is pulled backward the finger will be released from the hub *e'* and the central shaft permitted to turn and thereby operate the display devices; but when the plate *U* is normally pushed forward by means of a spring, *a*, the projecting finger will enter the notched hub *e'* and prevent the same from turning. The upper end of the shaft *C* extends to a distance about in line with the top of the table, said end being square in cross-section.

30 denotes the display device, which consists of the base 31, the tubular column 32, the enlarged circular casing 33, and the top 34.

35 denotes a tubular shaft having a hollow head square in cross-section at its top and extending downwardly through the column 32, and having a squared lower end.

36 denotes a coupling-piece, its opposite ends being square in cross-section, and which

connects the shaft 35 and the hollow shaft C, as shown. Thus it will be seen that the same motion applied to the hollow shaft C is imparted to the shaft 35.

5 The circular casing 33 is formed of the base-plate 38, and the circular vertical portion 39. The portion 39 is provided with a series of openings, 40, through which the picture, bill of fare, scriptural text, &c., may be readily 10 seen. A glass rim, 41, is placed inside the opening 40, as shown.

In connection with this display-case it is desired to arrange the advertisement or picture on a continuous tape or ribbon, which 15 ribbon is to have its objective parts so arranged that each pull upon the plate U will permit the turning of the ribbon one space—that is, to change from one opening to the other. To this end I arrange a central core, 20 42, an intermediate spool, 43, and a series of rollers, 44, arranged in a circle near the outer rim of the case 33, and fasten one end of the ribbon to the spool 43, pass it around the rollers 44, between them and the glass rim, and 25 pass it from them to the core 42, to which the opposite end is secured in a manner as will be presently described.

The spool 43 is provided with a key-seat, by means of which a key may be applied, and 30 the main body of the ribbon thereby be wound thereon.

For revolving the display-ribbon, I provide a hollow core, 42, (see Fig. 6,) with a projecting hub, 46, which is square in cross-section, and 35 which hub fits into the squared end of the tubular shaft 35. It is manifest that each partial turn of the shaft 35 will revolve the core 42, and thereby unwind a portion of the ribbon from the spool 43 and wind it upon itself.

40 As previously mentioned, the objective parts of the ribbon are so arranged that each movement of the gearing devices will turn the ribbon one space. Now, as the "objects" on the ribbons are each properly spaced in relation to the fixed openings in the sides of the 45 casing, it is manifest that if the core 42 were made of a solid body the ribbon in winding thereon would increase the diameter of the core at each turn, which would soon throw the

50 objective parts of the ribbon out of true alignment with the openings, and thereby prevent a clear representation thereof. To overcome this objection, I have provided a contractile core, which will automatically always present

55 the same diameter, whether the ribbon be at its first turn upon it or entirely wound upon the same. To this end I form the core 42 with a top plate, 48, and bottom plate, 49, and the four (more or less) segmental sections, 50.

60 These sections are each provided with a central slot, 51, which embraces a vertical stop-rod, 52, which limits the outward motion of said sections.

To conveniently secure one end of the ribbon to the core, I provide a recess, 70, in one of the sections, and a rod, 71, arranged to pass through the upper and lower plates, 48 and 49,

which is sealed in the recess 70, as shown in the drawings. The body portion of said rod 71 is of a cam shape in cross-section. (See 70 Fig. 7.)

In securing the ribbon, one end thereof is placed in the recess. The rod 71 is then passed through the top plate, through the recess, and with its cam portion 80 placed outward and 75 its lower end entered into the bottom plate. It (the rod) is then given a half-turn, which causes the cam portion to bear against the ribbons or tape, and thereby securely fasten the same to the core 42. The interior faces of 80 the sections 50 form a conical opening, 54, into which fits a hollow screw-plug, 55, having a conical-shaped upper portion which fits within the conical opening 54 and holds said sections 50 in proper concentric alignment. 85 The lower end of said screw-plug is screwed into a threaded portion of the shaft 35, and is provided at its upper end with a suitable hand-hold, 59, for screwing the same into position.

In the cap-plate 30 of the display device I 90 form a vertical socket, 60, adapted to receive the end of the screw-plug. The screw-plug having been placed in position, the cap-plate put in place, and the tubular shaft 35 caused to operate, the same will cause the screw-plug 95 (which is held from turning by means of the cap-plate) to gradually rise up, and each movement of the tubular shaft 35 (which acts as a nut upon the screw portion of the plug) will cause the screw-plug to rise, say, one thread, 100 which will decrease the diameter of the body of the contractile core a proportionate degree; but the addition of the ribbon thereupon will keep the entire diameter of the core and ribbon combined always the same, this operation 105 being repeated until the ribbon is all unwound from the spool 43, at which time the screw-plug will have risen to its highest point into the recess in the cap-plate and the main diameter of the body of the core 42 reduced to 110 its minimum. The cap-plate is then removed, the ribbon again wound upon the spool 43, the plug again screwed into position, the cap replaced, and the same is again ready for operation.

115 It will be understood that the hub e' (see Fig. 8) being provided with notches e² e² diametrically opposite, when the finger is released from one notch the shaft will give a half-turn, and the relation between the ribbon mechanism and the shaft is such that a one-half turn of the shaft will give the ribbon a turn equal to one space in the sides of the casing.

62 denotes the rod, which passes centrally through the several hollow shafts, and has its 120 lower end screwed into the frame, and has at its upper end a circular nut, 63.

From the foregoing description, taken in connection with the drawings, the operation and advantages of my improvement will be 125 readily understood.

Having thus described my invention, what I claim, and desire to secure by Letters Patent, is—

1. The combination, with the shaft C, connected at its upper end with and adapted to operate the display devices, a gear, e, and a notched hub, e', mounted upon the lower end 5 thereof, said gear e engaging with the spring-operated gear d², whereby the shaft C is revolved, said hub e' provided with notches e² e², arranged in diametrically-opposite edges of said hub, of the spring-actuated sliding plate 10 U, provided with a hand-hold at one end, its opposite end adapted to normally engage either of said notches e², substantially as and for the purpose set forth.

2. The combination, with the shaft C, connected at its lower end with and adapted to be revolved by the spring-actuated gearing, and the tubular shaft 35, connected to the display devices, of the coupling-section 36, connected at its lower end to the upper end of 20 shaft C and at its upper end to the tubular shaft 35, whereby the same revolution of shaft C is communicated to the tubular shaft 35, substantially as and for the purpose set forth.

3. The combination, with the shaft C, means, 25 substantially as shown, for operating said shaft, the tubular shaft 35, connected with the shaft C, said shaft 35 disposed within the column 32 of the display device 30 and provided with a squared recess in its upper 30 end, of the core 42, provided with a central squared hub, 46, fitting the squared recess in the shaft 35, said core disposed centrally with the casing 33 and having one end of the display-ribbon connected thereto and adapted 35 to wind the said tape upon itself, substantially as shown and described.

4. The combination, with the main table or frame, of the display device 30, said device consisting of a base, 31, a central hollow column, 32, projecting upwardly therefrom, an enlarged horizontal casing, 33, formed at the upper end of said column, provided with sight-openings 39 in the circular vertical rim thereof, said case adapted to receive the tape 40 or winding mechanism, the hollow shaft 35, operating in the tubular column, said ribbon devices connected to the shaft 35, said shaft 35 connected to the shaft C, and means for operating the several shafts and ribbon devices, substantially as shown and described.

5. The combination, with the tubular shaft 35, disposed within the column 32, and the casing 33, arranged above said column, of the central core, 42, connected with the upper 55 end of the tubular shaft 35, the spool 43, mounted within the casing 33 and adjacent to the core 42, the rollers 44, arranged within the casing 33, near the circular rim 40 and concentric with the central core and the ribbon, said ribbon connected at one end to the spool 43, passed about the rollers, between them and the vertical rim of the casing, and connected at its other end to the core 42, and means for revolving the said core, substantially as shown and described.

6. The combination, with the display-casing 33, a ribbon-winding spool, 43, mounted

therein, guide-rollers 44, disposed in a circle near the vertical rim of the casing, a ribbon wound upon the spool 43 and passing about 70 the rollers 44, said casing provided with a hollow column, 31, and a tubular shaft mounted in said hollow column, of the contractile core 42, said core disposed centrally within said casing and connected to the upper end of said 75 shaft 35, and connected with the free end of the ribbon, and means for revolving the shaft 35 and the core, substantially as and for the purpose set forth.

7. The combination, with the tubular shaft 80 35, the display-casing 33, the ribbon spool or roller 43, the ribbon-guide rollers 44, said rollers 43 and 44 disposed within said casing, of the contractile core 42, disposed centrally of said display-casing, said core formed of 85 segmental sections, said sections adapted to be contracted and expanded, the lower end of said core connected to the tubular shaft 35, and means for operating said shaft, all arranged substantially as and for the purpose 90 hereinbefore described.

8. The combination, with the tubular shaft 35, provided with a screw-threaded portion, the contractile core 42, formed substantially as described, and the casing 33 and cap-piece 95 38, said cap-piece 38 provided with a recess, 60, of the conical screw-plug 55, said plug adapted to be screwed at its lower end into the tubular shaft 35, its upper end formed conical and arranged to hold the several sections of the core in concentric circular alignment, said plug adapted to be automatically fed upward by the revolution of the tubular shaft, said plug 55 held from turning by its upper end projecting in the recess 60, said 105 shaft 35 connected with and operated by the shaft C, and means for operating said shaft, substantially as shown and described.

9. The combination, with the contractile core 42, the tubular shaft 35, connected therewith, said core and shaft disposed within the casing 33 and column 31 of the display device, and the ribbon-roller 43 and guide-rollers 44 arranged within said casing 33, said ribbon connected at one end to the roller 43, 110 wound thereon, and passed between the rollers 44 and the casing-wall 40, of the ribbon-fastening device, consisting of a recess, 70, formed in one of the sections 50 of the core 42, a rod passed through the heads 48 and 49 of the core-body and the recess 70, said rod formed with a cam portion, 80, adapted to press the free end of the ribbon against the side of the section, and means for operating said ribbon-moving devices, substantially as 115 120 125 hereinbefore described.

10. The combination, with the main frame, the hollow shaft C, the tubular shaft 35, connected with the upper end of said shaft C, the display device disposed above the frame, 130 said device provided with a hollow column surrounding the tubular shaft 35, an enlarged casing adapted to receive the ribbon winding and unwinding devices, and a cap-piece, 30,

of the tie-rod 62, said rod passing centrally through the shafts C and 35, the central core of the ribbon-display device, and the cap-piece, said rod screwed into the frame below the base of the table and provided with a squared end entering the cap-piece and provided with a securing-nut, 63, at its upper

end, whereby the several parts are securely held together, substantially as shown and described.
